UNITED STATES PATENT OFFICE.

GEORG PHILIPP JAEKEL, OF FRANKFORT-ON-THE-MAIN, GERMANY.

BOX OR CHEST.

SPECIFICATION forming part of Letters Patent No. 716,551, dated December 23, 1902.

Application filed November 8, 1901. Serial No. 81,643. (No model.)

To all whom it may concern.

Be it known that I, GEORG PHILIPP JAEKEL, a subject of the German Emperor, residing and having my post-office address at Lange-
strasse 25, Frankfort-on-the-Main, Germany,
have invented certain new and useful Im-
provements in Boxes or Chests, of which the
following is a specification.

The present invention relates to a box or
chest containing one or more drawers or trays,
and the invention lies in the particular ar-
rangement of the box in such a manner that
when the lid is raised the drawers are auto-
matically pushed outward or opened and when
the lid is closed the drawers are automati-
cally pushed back. A box of this kind with
several drawers arranged one above the other
is represented in the annexed drawings, in
which—

20 Figure 1 is a perspective view of the box-
casing in an open condition with the drawers
removed. Fig. 2 is a perspective view of the
box with the drawers in an open condition.
Fig. 3 is a cross-section of the box open, and
25 Fig. 4 is a partial cross-section of the box on
a larger scale.

In the box the desired number of drawers
a are arranged one above the other and are
movable in horizontal planes to their open
30 and closed positions. The lid of the box is
connected with a metal frame or lever c by
means of a hinge or joint b. The said frame
c forms a driving-arm which is moved for-
ward by the lid when the latter is opened
35 and pushes the lowermost drawer out of the
box - casing, which is open in front. The
drawer next above said lowermost one is con-
nected with the latter by a band e, Figs. 3
and 4, and a similar band connects the sec-
40 ond drawer and the third and so on. By this
means each drawer moves with it the drawer
immediately above, and in the end all the
drawers project in the form of steps and ex-
pose their contents to view.

45 For the purpose of returning the drawers,
&c., to their original positions when the lid
is let down the rear ends of the drawers, &c.,
are connected by bands h with the outer side
50 of the lid. On the latter being moved down-
ward the bands are pulled and move the
drawers back to their closed positions.

The arrangement can of course also be made

in such a manner that more than one drawer
is placed in each horizontal division of the
box, so that each compartment consists of 55
several drawers, all of which are, however,
moved forward and backward by means of
the lid. If the drawer in the uppermost di-
vision is vertically divided into two independ-
ent compartments f f, Figs. 1 and 2, the lat- 60
ter may instead of being arranged to be pushed
forward be pivoted to the lateral edges of the
box, and the lid may be provided with levers
g in addition to the main lever c, pushing out
the lower boxes, said levers g causing the 65
upper compartments to be swung out to the
right and left, respectively. These compart-
ments are also connected with the lid by
bands h, by means of which they are returned
to their closed positions. 70

It might occur that the band connecting
the undermost drawer with the lid is broken
or cut, whereupon the said drawer would be
loose and might fall out of the box. To pre-
vent this, a fixed hook i, Figs. 3 and 4, may 75
be provided at the rear of the bottom of said
drawer, and at the bottom of the box a lever
k, formed as a hook at one end, may be ar-
ranged in such a manner that when the lid
is closed the free end of said lever k is struck 80
by the frame or lever c, so that the said
free end is depressed and the hooked end
elevated, as indicated by dotted lines in Fig.
4. The hook of the lever k then engages the
hook i and holds the drawer fast even if the 85
band of the latter should be broken or cut.

The bands h, connecting the lid with the
various drawers, may be dispensed with and
the lever c pivotally connected with the low-
ermost drawer, a flat angle-iron or the like, l, 90
being arranged at the top, Fig. 3, to push the
lever c back when the lid is closed.

I declare that what I claim is—

1. The combination with a box or chest cas-
ing having a hinged lid, and drawers or trays 95
adapted to be opened and closed by the move-
ment of said lid, of a frame or lever attached
at one end to said lid and adapted to push
the lowermost drawer forward on the lid be-
ing opened, means for connecting each of said 100
drawers with the drawer next above and
means for returning each drawer to closed po-
sition on the lid being closed substantially
as described.

2. The combination with a box or chest casing having a hinged lid and drawers or trays *a* adapted to be opened and closed by the movement of said lid, of a frame or lever *c* revolvably attached at one end to said lid and adapted to push the lowermost drawer forward on the lid being opened, bands *e* connecting each of said drawers with the drawer next above, bands *h* connected with each of said drawers and with the lid for returning the drawers to closed position on the lid being closed and means for preventing the drawers from falling out in the event of breakage of the band *h* substantially as described.
- 15 3. The combination with a box or chest casing having a hinged lid and drawers or trays *a* adapted to be opened and closed by the movement of said lid, of a frame or lever *c* revolvably attached at one end to said lid and adapted to push the lowermost drawer forward on the lid being opened, bands *e* connecting each of said drawers with the drawer next above, bands *h* connected with the rear end of each of said drawers and with the outer 25 side of the lid for returning the drawers to closed position on the lid being closed, a hook *i* attached to the lowermost drawer and a pivoted lever *k* having a hooked end operated by the lever or frame *c* and adapted to engage said hook *i* for preventing the lower 30 gage said hook *i* for preventing the lower

drawer from falling out in the event of breakage of the band *h* substantially as described.

4. The combination with a box or chest casing having a hinged lid and drawers or trays *a* adapted to be opened and closed by the movement of said lid, of a frame or lever *c* revolvably attached at one end to said lid and adapted to push the lowermost drawer forward on the lid being opened, bands *e* connecting certain of said drawers with the drawer next above, bands *h* connected with the rear end of each of said drawers and with the outer side of the lid for returning the drawers to closed position on the lid being closed, upper drawers or trays hinged to the 45 casing, levers *g* connected to the lid for operating said latter drawers, a hook *i* attached to the lowermost drawer and a pivoted lever *k* having a hooked end, operated by the lever or frame *c* and adapted to engage said hook *i* for preventing the lower drawer from falling out in the event of breakage of the band *h* substantially as described.

In testimony whereof I have signed my name to this specification in the presence of 55 two subscribing witnesses.

GEORG PHILIPP JAEKEL.
